UNITED STATES PATENT OFFICE.

HERBERT ABRAHAM, OF NEW YORK, N. Y., ASSIGNOR TO FRANK J. AROMENAKER AND
GRANT M. KROMENAKER, OF CHICAGO, ILLINOIS.

ROOFING.

Application filed March 8, 1923. Serial No. 623,663.

To all whom it may concern:

Be it known that I, HERBERT ABRAHAM, a citizen of the United States, residing at the city, county, and State of New York, have invented a certain new and useful Improvement in Roofing, of which the following is a specification.

This invention relates to certain improvements in roofings of the character disclosed in patent application Serial No. 500,157, filed September 12, 1921, by Frank J. Kromenaker and Grant M. Kromenaker.

That application describes rectangular roofing strips slotted to form tongues in one of their longitudinal edges, and intended to be laid in overlapping courses. When laid, the tongues of any strip partly overlap a strip of the next higher course with their ends covered by a strip of the succeeding course, thus producing a pleasing interwoven effect.

However, to attain the desired appearance, considerable care must be exercised in laying the roofing. The strips of the first course must be laid with their ends overlapped to such extent that the distances between the tongues of adjacent strips will be exactly uniform. This requires careful measurements on the part of the roofer and somewhat slows down the speed of laying the roof. The second course, as well as the succeeding courses, must be laid that the tongues of each strip come exactly midway between the tongues of the strips of the course below.

My improvement aims to facilitate laying by providing strips of such form as to be self-spacing with respect to adjacent ones of the same row or course, and to be self-aligning with regards to those of successive courses.

With these and other objects in view, my invention consists in the provision of strips of rhomboidal form hereinafter described and claimed, it being understood that modifications may be made without departing from the scope of the invention.

In the accompanying drawings, illustrating a preferred embodiment:

Figure 1 is a plan view of a single strip;

Figure 2 is a plan view of two strips laid with their ends overlapped;

Figure 3 is a plan view of two strips of successive courses; and,

Figure 4 is a plan view of several strips 55 in interlapped relation.

The strips are made of any suitable weather-resisting and waterproof prepared roofing material, and they are rhomboidal in shape.

As in the case of the roofing of which this is an improvement, slits 10, arranged in pairs, are cut into the strip from one of its longitudinal edges 11 to a depth which is more than midway toward the opposite edge 12, thereby forming alternating tongues 13 and so-called slabs 14.

My improvement consists in the provision of a strip of the character described having its longitudinal edges 11 and 12 offset relatively to each other a distance equal to the extent of the lap between the adjoining shingles of a course, when laid, and having parallel oblique end edges 15 and 16 which are so disposed with relation to the slits 10 75 as to provide a strip that is both self-spacing and self-aligning.

It will be noted, on referring to Fig. 1, that the horizontal distance (x) from the upper left-hand corner to the nearest slit 80 10, or point a^1 , is equal to the extent that the ends of adjacent strips are overlapped when laid in a row, to form a course, as seen in Fig. 2. Furthermore, the distance (y) from the upper right-hand corner a^2 to the nearest slit 10 is equal to the width, measured horizontally, of a slab 14, or in other words, to the distance between adjacent tongues 13.

The obliquity of the ends is such that when the lower right-hand corner b^1 of a strip registers with the lower end b^2 of the right-hand slit 10 of one of the tongues 13 of the strip below, as seen in Fig. 3, then the tongues of the two strips will be equally spaced with respect to each other. It will be observed that by merely registering the point b^1 of any strip with the point b^2 of the strip immediately below, the tongues of the several strips are without further effort brought into proper relation.

In laying the strips of any course, the left-hand end 15 of each strip is lapped over the right-hand end 16 of the adjacent strip with the point a^1 of the first-mentioned strip superposed upon the point or corner a^2 of the latter, as shown in Fig. 2. This automatically provides the proper overlap without necessity of any measuring. As the ends

15 and 16 are parallel, the lap is of uniform width throughout. Furthermore, when the ends are lapped as described, the joints will fall in such position as to be completely covered by portions of the strips of the next lower and the next upper courses. For example, on referring to Fig. 4 it will be noted that the joint between the two strips of the intermediate course B is completely concealed by portions of the strips of the first course A and the third course C. The strips are so designed that each one must overlap the preceding one in the right way. If for any reason the overlapping is carried out improperly, then the error would be self-evident, since the edge 16 would extend beyond the tongue, and being visible could be corrected immediately.

What I claim is:

20 1. A roofing strip of rhomboidal shape having tongues and intervening slabs along one of the longer edges, the tongue nearest one end being spaced from said end a dis-

tance defining the proper extent of the overlap of adjoining strips of a course when laid, 25 the tongue nearest the opposite end being spaced from said opposite end a distance substantially equal to the width of a slab measured in the direction of length of the strip, the opposite longer edges being offset 30 relatively to each other a distance equal to the extent of overlap of adjoining shingles when laid.

2. A roofing strip of rhomboidal shape having tongues and intervening slabs along 35 one of the longer edges, the tongue nearest one end being spaced from said end a distance defining the proper extent of overlap of adjoining strips of a course when laid, the tongue nearest the opposite end being spaced from said opposite end a distance 40 substantially equal to the width of a slab measured in the direction of length of the strip.

HERBERT ABRAHAM.
